(57) **CLAIM**

I claim the ornamental design for the step-through bathtub insert, as shown and described.

DESCRIPTION

FIG. 1 is a top plan view of said bathtub insert;
FIG. 2 is an elevated front view thereof;
FIG. 3 is an elevated back view thereof;
FIG. 4 is an elevated right end view thereof, the left end being a mirror image of the right side; and,
FIG. 5 is bottom plan view of said bathtub insert.
